UNITED STATES PATENT OFFICE.

JOHN C. HALL AND CHARLES O. TANNER, OF CINCINNATI, OHIO.

FOLDING BEDSTEAD.

SPECIFICATION forming part of Letters Patent No. 251,113, dated December 20, 1881.

Application filed November 8, 1881. (No model.)

To all whom it may concern:

Be it known that we, JOHN C. HALL and CHARLES O. TANNER, both of Cincinnati, Hamilton county, Ohio, have invented a new and 5 useful Improvement in Folding Bedsteads, of which the following is a specification.

Our invention relates to improvements in those articles of furniture which on one side are adapted for use as a desk, book-case, wardrobe, or the like, and which on their other side are capable of conversion into a bed.

In the accompanying drawings, Figure 1 is a side elevation of an article of furniture embodying our invention, the bed being unfolded. 15 Fig. 2 is a vertical section of the same, with the bed folded and the desk unfolded. Fig. 3 represents, in elevation, one-half of the rear of the article, with the bed folded. Fig. 4 represents, in elevation, one-half of the front, the desk being represented open. Fig. 5 is a vertical section on the line *x x*.

The article consists externally of an inclosing case or shell whose lower portion or base, A, is of somewhat greater horizontal dimensions from front to rear than is the upper and larger portion, B. This case is provided underneath with casters C.

Extending athwart the interior of the case from side to side, at the upper portion thereof, is a partition, D, which may serve for attachment of shelves E, accessible through an opening, b, provided with doors F. Another opening, b', may be closed by a flap, G, which, being pivoted, as at *g*, to the frame, can be let down, as in Fig. 2, to constitute a convenient desk. The lowermost shelf, E', is purposely so located as to serve as a stop or bearing for the rear edge of the desk G, so as to hold it to the desired slope when open, as shown in Fig. 35

40 2. A wardrobe, a lavatory, or any other convenience may be substituted for the said appliances E and G, or either of them.

The lower portion, A, of the case, extending farther rearward than the portion B, presents 45 an offset, *a*, to which is hinged or pivoted, at H, the frame J of our bed. This frame consists, principally, of four boards, rectangularly united, as shown, and stiffened by two cross-pieces, K K', of which the piece K affords a 50 means of attaching the hinges H, while the

piece K' affords a place of attachment for the hinges L of two folding feet, M, which are held to the unfolded position when the article is to be used as a bed by hooks N, which are engaged within staples O.

Upon the cross-pieces K K' are placed any suitable bed-slats, P, (separated by interstices P'), for any bed-bottom or mattress.

The location of the hinged attachment of the bed-frame some distance from its head enables 60 the utilization of the portion A of the case by its occupation by said head portion in the folded condition of the bed, as shown in Figs. 2 and 3. It also, to an appreciable extent, relieves the operator from some of the labor of 65 handling the bed by the counterbalancing effect of said head upon the remaining portion. This location of the hinged attachment is further beneficial in the firm support it affords to that part of the bed which has to sustain the 70 main weight of the occupant.

The under side of the folded bed, being presented toward the rear of the piece of furniture, and consequently out of sight during the day-time, may be constructed in the open manner shown at P' in Figs. 3 and 5, which open construction, in conjunction with the open space Q (left free for the sweep of the foot-board) and the open space Q' below the partition D, insures a sufficient circulation of air to 75 keep the bedding at all times well ventilated.

We claim herein as new and of our invention—

1. In combination with the case A B, having the rear offset, *a*, the folding bed J K K', 85 hinged at H at some distance from the bed-head and supported in the unfolded condition by the folding feet M, substantially as set forth.

2. The folding bed J K K', with its inclosing and supporting case A B, so formed and arranged as to leave the open ventilating-spaces P' Q Q', in the manner explained.

In testimony of which invention we hereunto set our hands.

JOHN C. HALL.
CHAS. O. TANNER.
